UNITED STATES PATENT OFFICE.

WALTER P. MURPHY, OF NEW YORK, N. Y.

HOPPER-CAR.

1,377,783.

Specification of Letters Patent.

Patented May 10, 1921.

Application filed July 29, 1919. Serial No. 314,055.

To all whom it may concern:

Be it known that I, WALTER P. MURPHY, a citizen of the United States, residing at New York, in the county of New York and State of New York, have invented certain new and useful Improvements in Hopper-Cars, of which the following is a specification.

My invention relates to hopper cars of metal construction. Cars of this type are constructed in various ways but with the general purpose of dividing the space within the car body into a number of discharging chutes or hoppers having openings closed normally by hinged doors, through which openings the load is dumped. The fixed portions of the bottom of the car consist of inclined sheet metal structures, or slope sheets, which are arranged so as to direct the cargo to one or other of the discharge openings. Cars of this type are frequently loaded by means of clam shell buckets, or other loading or conveying devices, which drop their charges often at a considerable distance above the car. As a result the bottom sections or slope sheets of the car are soon worn, broken or otherwise injured and made unserviceable.

One of the principal objects of the present invention is to strengthen these portions of cars of this general type so as to thereby increase their durability under service conditions.

The invention consists of the new and improved constructions, arrangements and devices to be hereinafter described and claimed for carrying out the above stated objects and such other objects as will appear from the following description of certain preferred embodiments of the invention as shown in the drawings. For the purpose of illustrating the invention in a typical form my improvements have been shown in connection with a hopper car which in other respects is of familiar construction. It will be realized, however, that the invention is not to be limited to this particular species of car.

In the drawings,

Figure 1 is a fragmentary perspective view of a hopper car having the slope sheets and door constructed in accordance with this invention.

Fig. 2 is a sectional view on line 2—2 of Fig. 1, the scale being enlarged.

Fig. 3 is a similar view illustrating a modification.

Like characters of reference designate like parts in the several figures of the drawings.

Referring to the drawings—

10 designates one of the side walls of a car and 11 one of the end walls thereof. In the car of the general design illustrated, the space between the side and end walls is divided into four discharging hoppers or chutes each having a discharge opening. 65 The drawings are fragmentary, showing one end of the car only. Each discharge opening is normally closed by a door and these doors are operated in pairs, the doors at each end of the car being connected by a 70 common cross beam. Longitudinal and transverse structures divide the bottom of the car into the four discharge hoppers mentioned. All of this is a matter of common construction. It will be sufficient to 75 describe in detail a novel feature of the car, confining attention to one end of the car as shown in the drawings.

The end bottom section or panel 12 of the car slopes from the end wall 11 down to the 80 discharge openings 13 and consists preferably of a flat central strip 14 and two side plates or slope sheets 15, 15. This structure is riveted to the side and end walls in the usual way and is sustained by supporting 85 devices which need not be described in detail. The longitudinal structure dividing this end of the car body into the two discharging hoppers mentioned consists of a sheet metal member 16 pressed to approximately V-shape in cross section and triangular side plates 17 which are riveted to the slope sheets 15. The outer walls of the discharge hoppers are composed of plates 18. The bottom part of the space within 95 the car body is divided by a transverse structure consisting of two oppositely inclined panels 19, 19 which slope downwardly toward the discharge openings. Each of the panels 19 consists preferably of a middle 100 sheet or plate 20 and side plates or slope sheets 21, 21.

It will be clear that the sloping sections 12, 19 will be subject to considerable wear and tear especially when the car is loaded 105 by dropping heavy charges of material such as coal or ore into the same from a clam shell bucket, or other loading device. This

will be particularly the case with the bottom panel 12 because of its considerable length and gradual inclination. Moreover, these portions of the car, especially the end 5 bottom panel 12, have to carry the weight of the cargo in transit and are subject to wear when the cargo is discharged. To increase their strength and durability these portions 10 of the car structure are provided, in accordance with my invention, with rigidifying corrugations. For example, the slope sheets 15 may be provided, as shown in Figs. 1 and 2, with a plurality of parallel longitudinally extending corrugations 22 which 15 merge one into the other so as to give the sheets a sinuous configuration in cross section, the corrugations terminating within the edges of the sheets so that they act effectively as beams. In the figures mentioned 20 the corrugations run longitudinally of the sheets, that is, in the direction of the movement of the load in discharging so that they do not interfere with, but rather facilitate, the dumping of material from 25 the car. If desired, the middle slope sheets 21, 21 may also be provided with like rigidifying corrugations 23.

In Fig. 3 an arrangement is shown in which the slope sheets 15^b, 15^b are formed 30 each with two sets of diagonally disposed corrugations 26 which extend from the lateral edges of the sheet toward the center thereof and downwardly toward the discharge openings; the sheets being preferably 35 formed also each with a central longitudinal strengthening rib or corrugation 27. By this arrangement the sheets are rigidified both longitudinally thereof and also transversely, and the disposition of corrugations 40 is such as to interfere very little, if any, with the movement of the load in discharging. The slope sheets 21^b, 21^b at the middle of the car may be provided with a similar arrangement 45 of longitudinal corrugations 28 and diagonal corrugations 29.

A corrugated sheet metal door 30 is provided for closing the discharge opening 13 which is hinged to the car body at 32, but as this structure is not claimed herein, being 50 the subject matter of a copending application filed Feb. 9, 1921, Serial No. 443,691, as a division hereof, detailed description of the same herein is unnecessary.

I claim:

1. In a railway car of the character described, the combination with the end and side walls of the car, of means constituting a hopper having a discharge opening comprising a sheet metal panel which slopes toward 55 said discharge opening and is formed with rigidifying corrugations which extend substantially in the direction of movement of the load when discharging.

2. In a railway car of the character described, the combination with the end and

side walls of the car, of means constituting a hopper having a discharge opening comprising a sheet metal panel which slopes toward said discharge opening and is formed with rigidifying corrugations which are 70 parallel and extend substantially at right angles to the edge of said panel along said discharge opening.

3. In a railway car of the character described, the combination with the end and 75 side walls of the car, of means constituting a hopper having a discharge opening comprising a sheet metal panel extending from the end of the car toward the middle and sloping downwardly toward said discharge 80 opening, and a panel on the other side of the opening sloping thereto, both said panels being formed with rigidifying corrugations which extend generally in the direction of movement of the load when discharging. 85

4. In a railway car of the character described, the combination with the end and side walls of the car, of means constituting a hopper having a discharge opening comprising a sheet metal panel extending from 90 the end of the car toward the middle and sloping downwardly toward said discharge opening, and a panel on the other side of the opening sloping thereto, both said panels being formed with rigidifying corrugations 95 which are at right angles to the edges of said panels on opposite sides of said discharge opening.

5. In a railway car of the character described, the combination with the end and 100 side walls of the car, of means constituting a hopper having a discharge opening comprising a sheet metal panel which slopes toward said discharge opening and is formed with rigidifying corrugations which are 105 diagonally disposed in the panel.

6. In a railway car of the character described, a hopper structure having a discharge opening formed in part by a slope sheet formed with a plurality of diagonally 110 disposed rigidifying corrugations.

7. In a railway car of the character described, a hopper structure having a discharge opening and formed in part by a slope sheet provided with two sets of diagonally disposed corrugations which extend from the lateral edges of the sheet toward the center and toward the discharge opening. 115

8. In a railway car of the character described, a hopper structure having a discharge opening and formed in part by a slope sheet provided with two sets of diagonally disposed corrugations which extend from the lateral edges of the sheet toward the center and toward the discharge opening and with a longitudinally extending corrugation between said sets of diagonal corrugations. 125

9. In a railway car of the character de- 130

scribed, the combination with the side and end walls of the car, of an end bottom panel comprising two sheets formed with rigidifying corrugations and a flat sheet between them, a longitudinal structure dividing this end of the car into two hoppers, each having a discharge opening, an intermediate panel on the other side of said openings in-

clined thereto and formed with rigidifying corrugations, side plates forming the outer 10 sides of the hopper, and doors for closing said discharge openings each comprising a sheet metal plate formed with rigidifying corrugations.

WALTER P. MURPHY.
